PISTON AND ROD CONNECTION FOR PUMPS

Victor R. Heftler, Grosse Pointe Park, Mich.

Application January 7, 1941, Serial No. 373,459,
 which is a division of application Serial No.
 348,431, July 30, 1940. Divided and this applica-
 tion August 8, 1942, Serial No. 454,166

4 Claims. (Cl. 309—17)

This application is a division of my co-pending application No. 373,459, filed January 7, 1941, which latter is a division of my co-pending application No. 348,431, filed July 30, 1940.

It is an object of this invention to provide a simple and inexpensive construction for the accelerating pump usually provided in carburetors.

Fig. 1 is a side elevation of a carburetor embodying my invention, viewed from the lower side of Fig. 2.

Fig. 2 is a plan view, with one half of the cover removed.

Fig. 3 is a front elevation, viewed from the left side of Fig. 2, with some portions cut away showing the piston of the accelerating pump in its upper position.

Fig. 4 is a fragmentary elevation from the same point of view with the pump piston in its lower position.

Fig. 5 is a so-called exploded view, in perspective and on an enlarged scale, of parts of the accelerating pump.

Fig. 6 is an elevation, viewed from the right side of Fig. 2, with some portions in cross section along parallel lines 6a, 6b, 6c and 6d of Fig. 2.

Fig. 7 is a partial cross section along the polygonal line 7—7 of Fig. 2.

Fig. 8 is a plan view of the washer and valve retainer.

This invention is described as applied to a downdraft carburetor, comprising a throttle housing member 21, provided with a flange 22 for attachment to an engine manifold, not shown, in the well known manner, over which is secured a mixing chamber body member 23, which supports a cover member 24, these three main parts being fastened to one another, by screws 25 for instance. A heat insulating gasket 52 is preferably inserted between the throttle housing 21 and the mixing chamber body member 23.

The air supply enters through conduit 26 in the cover member 24, being controlled by choke valve 27. Conduit 26 registers with conduit 30 (Fig. 6) in the mixing chamber body member 23, which leads to conduit 31 in the throttle housing member 21.

A throttle valve 32, mounted on shaft 33, controls the passage of the mixture through the carburetor. The means used to actuate the throttle are not shown, they may consist of a lever fastened to shaft 33. To limit the movement of the throttle there is fastened on shaft 33 a lever 34, provided with lugs 35 and 36. Lug 35 co-operates with stop pin 37 to limit the opening movement, while a screw threaded in lug 36 co-oper-

ates with part 39 to limit adjustably the closing movement.

Formed in the mixing chamber body member is constant level fuel chamber 62. A pair of floats symmetrically located with reference to the median plane of the carburetor is used to control a fuel inlet in the well known manner. One of these floats is shown at 65 on Fig. 2.

The main normal mixture supply of fuel is effected through a double venturi shown on Fig. 6, but need not be described here nor is it pertinent to describe in detail the provision made for idling or for the control thereof.

To provide an additional supply of fuel for acceleration, a pump, actuated by the throttle, is provided. The mixing chamber 23 is bored at 119 (Fig. 7) to receive a pump liner 120. A gasket 121 is placed between the bottom of hole 119 and the end of liner 120, which is retained in position by the split elastic ring 122. A ball 123 in recess 124 forms a valve which opens to allow fuel to flow through channel 125 from the fuel chamber 62 into the pump but prevents reverse flow. To prevent too great a movement of the ball valve, it is retained in recess 124 by a diametral web of the gasket 121, shown at 126 in Fig. 8. As Fig. 7 is a cross section on a polygonal line, it is not possible to show there how channel 125 is drilled from the outside of the casting, but reference 127 on Fig. 1 indicates both the start of said drilling and the plug used to close it.

A piston 128 is adapted to slide in the pump cylinder liner, being actuated by piston rod 129. Piston 128 is drilled and counterbored to form a seat 130 upon which diaphragm 131 is held by elastic split ring 132.

Adapted to reciprocate in a vertical hole in the mixing chamber body member and guided thereby is a pump rod 135 to which is riveted a bracket 40 136 provided with slot 137 and downwardly bent ears 138. The piston rod 129 is formed with a head 133 and a neck 134. Diaphragm 131 is a sheet metal stamping provided with a stepped aperture wide enough at 160 to admit the end 45 164 of the piston rod and narrow at 161, in the center of the diaphragm, so as to just admit the neck 134 of the piston rod. A spring 139 surrounds the piston rod and is compressed between diaphragm 131 and bracket 136; the top end of the spring is inserted between the ears 138 and the rod to hold the latter against lateral displacement; the lower end of the spring is likewise held by the upturned fingers 140 of the diaphragm and prevents lateral displacement of the 50 lower end of the piston rod.

To assemble the parts, a sub-assembly is first made comprising the piston 128 and the diaphragm 13 which is held down on the seat 130 by the split ring 132.

This first subassembly being made, the piston rod 129 surrounded by spring 139 is inserted through the wider portion of the diaphragm aperture until the neck 134 of the rod can be inserted laterally into the narrower portion 161 of the aperture, whereupon the spring 139, which was held slightly compressed to clear the top of fingers 140, is released and allowed to slip between said fingers and the piston rod.

The spring 139 is then compressed down to permit the insertion of the top of the piston rod into the slot 137 of bracket 136, after which the spring is released to slip between ears 138 and the piston rod.

It will be seen that when the pump rod 135 is moved downwards, its movement is transmitted to the piston by the spring, as the piston rod is free to slide between the sides of slot 137. When the pump rod 135 is moved upwards, it is the piston rod that transmits the movement.

It will also be seen that this arrangement provides a certain amount of flexibility, so that the piston may be made a close fit into the cylinder liner, even though the latter may not be absolutely parallel to the hole that guides the pump rod 135.

The pump piston is actuated, through the pump rod 135, by a linkage made up of walking beam 141, fulcrumed at 142 on the throttle body member, and terminating in a slot to engage pin 143 in the lower slotted end of pump rod 135, of lever 144 fastened to throttle shaft 33 and of connecting link 145, articulated on the walking beam at 146 and on lever 144 at one of the two (or more) holes 147 and 148.

Upon opening the throttle, this linkage will move the piston downwards and the fuel in the pump cylinder will be forced through channel 149, Fig. 7, past outlet valve 150 into slanted hole 151 and through accelerating nozzle 152, Fig. 6, into the main air conduit.

I claim:

1. A piston, a piston rod, means to move said piston rod and means to secure said piston rod to said piston comprising an elastic friction member having a cylindrical friction surface parallel to said piston.

2. A hollow piston having a diaphragm secured thereto, a piston rod having a neck of reduced size, an aperture located centrally in said diaphragm to receive said neck, an off center aperture in said diaphragm wider than the piston rod and communicating with said first named aperture, slidable means surrounding said piston rod and a pair of protuberances on said diaphragm adjacent said second named aperture to hold said piston rod against lateral displacement when said slidable means are inserted between said rod and said protuberances.

3. A piston having a diaphragm secured thereto, a piston rod having close to each of its ends a portion of smaller size than the adjacent end, an eccentric aperture in said diaphragm wider than one end of said rod, a central aperture in said diaphragm connected to said eccentric aperture to admit only the rod portion of reduced size adjacent said end, slidable means surrounding each end of said rod, a pair of protuberances on said diaphragm to hold said rod against lateral displacement when said slidable means are inserted between said rod and said protuberances, a bracket having a slot to admit the portion of said piston rod of reduced size adjacent the other end thereof, a pair of protuberances on said bracket to hold said other end against lateral displacement when said slidable means are inserted between said rod and said protuberances and means to actuate said bracket.

4. A hollow cylindrical piston, a diaphragm held thereunto by frictional means in which the frictional surface is substantially parallel to the generatrices of the cylindrical outer surfaces of the piston and means engaging said diaphragm to actuate said piston.

VICTOR R. HEFTLER.
